ROTARY DISK BIT

Walter A. Abegg, Los Angeles, Calif., assignor of
one-half to Baldwin Reinhold, Los Angeles,
Calif.

Application May 12, 1934, Serial No. 725,372

10 Claims. (Cl. 255—71)

This invention relates to well drilling apparatus, and particularly pertains to a rotary disk bit.

In the operation of well drilling equipment, particularly such equipment as is used in the drilling of oil wells, it is necessary that the cutting members shall be particularly adapted to act upon the formation being penetrated and that these members, together with the means by which they are supported shall be durable, and of rugged character, permitting them to be readily assembled, and to maintain in complete functioning arrangement under extreme working conditions. It is also desirable to provide a disk bit structure which may be readily and inexpensively manufactured, and which is so designed as to lend itself to a rapid and convenient interchange in replacement of parts, and to an assembly which will insure that the entire bit structure will be of rigid character, while utilizing a minimum amount of material, and will not be subjected to weakening strain.

It is a further object of the present invention to provide a water course arrangement, making it possible to readily control the water course, and to interchange the water course outlets in the event that they should become abraded or otherwise mutilated in the course of operation of the drill bit.

The present invention contemplates provision of a drill disk through which water courses are formed, which courses terminate in communication with a water course insert, said bit terminating at its lower end in a pair of spaced legs, each of which independently supports a cutter disk bit and cutter disks as desired, the pins of said legs being preferably opposite laterally with relation to each other.

The invention is illustrated by way of example in the accompanying drawing, in which:—

40 Figure 1 is a view in side elevation showing the bit with which the present invention is concerned.

Fig. 2 is a view in elevation showing the bit as viewed at right angles to Fig. 1 and with parts of one leg broken away to more clearly show the 45 bit construction.

Fig. 3 is a view in plan showing the bit structure.

Fig. 4 is a view in vertical section and elevation as seen on the line 4—4 of Fig. 2.

50 Fig. 5 is a view in elevation as seen on the line 5—5 of Fig. 2, showing the lock nut arrangement.

Fig. 6 is a view in end elevation showing the key formed upon the outer disk bushing.

55 Fig. 7 is a view in end elevation showing the lock faces formed on the inner lock nut.

Referring more particularly to the drawing, 10 indicates the pin of the drill bit 11. This pin is of the usual tapered and threaded construction adapted to be threaded into the lower end of a connection carried by a drill string. The body 5 portion of the drill bit as indicated at 12 is cylindrical in cross section and terminates at its lower end in a substantially square sectional part 13. This portion is bifurcated to form a pair of disk supporting legs 14 and 15, having a space 16 between them. These legs each carry a pin 17, although as seen in Fig. 1 of the drawing, these pins are opposite and equidistant from the longitudinal center line of the bit, while their longitudinal axes are parallel and lie in the same horizontal plane, which is transversely disposed with relation to the longitudinal axis of the bit. As here shown, the inner and outer faces of the legs are parallel, each leg being formed with an opening 18 to receive the corresponding disk pin 17. The outer face of each leg is formed with a counterbore 19 to receive the cylindrical end of a bushing 20. The end of the bushing, as shown in Fig. 6 of the drawing, is formed with a transverse key slot 21. The slot 21 extends transversely of the end of the bushing 20, making it possible for the bushing to be reversed when it becomes worn on one side as it tends to do during operation. This slot meshes with a key 22 which is preferably inserted through slots formed radially through the legs 14 and 15 and extending downwardly from the opening provided for the pins 17. This key will therefore engage the portions of the keyway below the pins 17. The outer end of the bushing 20 is enlarged as indicated at 23 and fits within an enlarged counterbore 24 of a cutting disk 25. A center opening through the bushing receives the pin 17, the outer end of the pin being formed with an enlarged hexagonal head 26 by which the bushing is held in position. The inner end of each of the pins 17 is provided with a combined bushing and lock nut 27 which, as shown in Fig. 4 of the drawing, has a cylindrical extension formed with diametrically flat sides 28 adapted to fit between legs 29 of an inside washer 30 which is welded into a recess in the inner face of each of the legs 14 and 15. By this arrangement the inner threaded end of the pin 17 may be screwed into the bushing 27, and at the same time it will be insured that the lock bushing will be held against rotation, even though disposed in a place somewhat inaccessible for the use of a wrench or other holding tool.

An enlarged flange 31 of the lock bushing 27 seats within a counterbore of a core cutting disk 55

32, a pair of which disks are held for independent rotation in the space between the legs 14 and 15. In order to insure that the lock bushing 27 will be held in a locked position, the ends of 5 the pins 17 are formed as shown in Fig. 5 of the drawing, with a plurality of cotter pin openings 33, any one of which may receive a cotter pin 34.

The opposite sides of the hub portion of the 10 lock bushing 27 are cut away, as indicated at 35, to form hub segments 50 and 51. These segments are rounded at their inner edges as indicated at 52 to afford additional accommodation 15 for the cotter pins 34 which are used to lock the lock bushing 27 into position, it being understood that the cut away portions of the hub as indicated at 35 are provided to accommodate the cotter pins. It is also desirable as shown in Fig. 20 5 of the drawing, to recess the ends of the pins 17 as shown at 53 so that the cotter pin holes will not meet in a series of closely convergent angles.

In the operation of tools of this construction 25 it is desirable to prevent any portion of the cone being formed from packing against the parts in an objectionable manner and the end disks of the lock bushing 27 are therefore formed with a pair 30 of cutting teeth 54. These cutting teeth are offset from a transverse center line which intersects the axis of rotation of the disks, and the teeth extend substantially parallel to this center line at opposite sides thereof. These teeth as here shown are of the height of the hub on the lock bushing 27, and extend outwardly to the 35 edge of the flange thereof, being slightly hooked in the direction of rotation of the bit. The amount of offset is equal to the amount of offset of the axis of the pin 17 on which the lock bushing is mounted from the central rotating axis of 40 the drill bit. This insures that the lowermost of these teeth will be disposed in substantially the same plane as that of the rotating axis of the bit and will cut away any amount of core which might be otherwise formed therebeneath.

45 It is practice in drill bit constructions to incorporate water courses for the circulating mud through the drill bit to the disks, and since these are placed within the body of the drill bit it makes it necessary to provide a bit of relatively 50 large dimension. In the present instance, means have been provided to simplify the embodiment 55 of water courses in the drill bit construction without making it necessary to weaken the parts or proportionately increase the dimensions of the parts. This is accomplished by providing one central water course, as indicated at 36, which extends downwardly through the pin and the 60 cylindrical body portion 12 of the drill bit where it communicates with a transversely extending tapered passageway 37. This passageway is provided to accommodate a tapered water course insert 38, preferably of non-abrasive steel. This insert is formed with an opening midway its 65 length, and on one side thereof, and indicated at 39, which opening communicates with the lower end of the water course 36. A pair of divergent water course passageways 40 and 41 are formed through the insert 38 to a substantially diametrically opposite side from the opening 39. 70 Due to the length of the insert 38 the lower discharge ends of the diverging water courses 40 and 41 occur at points shown at sides of the drill bit and are so designed as to project a stream of mud laden fluid downwardly and outwardly, one stream for each pair of bits 25 and 31.

75 It will also be evident that the water course insert 38 may be readily removed and interchanged as desired.

It is preferable to form the outer surface of the insert tapered so that it may be driven into a correspondingly tapered hole of the tool bit body 11. In some instances it may be desirable to provide additional locking means for the insert and this may be a pair of cap screws 42 and 43 screwed into the body of the bit 11 at diametrically opposite sides of the insert and resting upon shoulders of the insert formed by scollops 44.

In operation of this drill bit the cutters 25 and 32 are mounted upon the legs 14 and 15 of 15 the bit by the pins 17. It will be seen that as the pins are tightened they will draw the bushings inwardly so that the keys and keyways 21 and 22 of the legs and on the ends of the bushings, respectively, will be placed in interlocking position 20 and will hold the bushings against rotation. This will not make it necessary to have slotted keyways in the bushing which might weaken it. The inner bushing nut 31 will be held against rotation by the member 30, and when the pins are 25 tightened a cotter pin 34 may be passed through an opening in the end of the pin to hold the structure against release.

30 It will be understood that the spacing of the bushings will make it possible for the cutter disks 25 and 32 to freely rotate upon them as may be brought about by rotation of the entire drill bit structure upon its vertical axis.

35 It will thus be seen that the drill bit structure here shown provides offset mountings for cutter disks without the necessity of specially machined eccentric parts, and that furthermore, the drilling operation may be carried on while the cutter disks are firmly secured upon their mountings in a manner to insure against weakness of 40 the parts, or weakness in the construction of the bit body itself. It will also be seen that in the operation of the bit, the tapered water course insert may be so designed as to properly deliver 45 a stream of circulating fluid to the bits without necessitating the introduction of delivery means between the two legs of the bit body and without weakening the bit body by water courses through the legs. In the event that the water course insert becomes mutilated or otherwise damaged, 50 to be rendered unsatisfactory for use, it is possible to quickly remove the insert and install another one, since it is desirable that the insert itself shall be made of hardened steel and may be easily handled, as well as designed to withstand considerable wear and rough usage.

55 It will thus be seen that the invention here disclosed is simple in its construction, does not require the use of any complicated or expensive machined parts, and is so designed as to insure 60 that the entire bit structure will be rugged and will not be subjected to undue strain incident to its operation.

65 While I have shown the preferred form of my invention, as now known to me, it will be understood that various changes may be made in combination, construction, and arrangement of parts without departing from the spirit of my invention as claimed.

70 Having thus described my invention, what I claim and desire to secure by Letters Patent is:—

75 1. A rotary drill bit for drilling wells comprising a body carrying cutter means at the lower end thereof, a water course extending longitudinally of said body, a transverse passage-

way extending entirely through the body of the drill and intersecting the water course at its lower end, and a tapered straight insert pin positioned within said transverse opening, said insert being formed with passageways communicating with the water course and directing fluid therefrom to the cutting tools.

2. A rotary drill bit for drilling wells comprising a body carrying cutter means at the lower end thereof, a water course extending longitudinally of said body, a transverse passageway extending entirely through the body of the drill and intersecting the water course at its lower end, and a tapered straight insert pin positioned within said transverse opening, said insert being formed with passageways communicating with the water course and directing fluid therefrom to the cutting tools, and means for detachably securing said insert in position.

20 3. A rotary drill bit for drilling wells comprising a body carrying cutter means at the lower end thereof, a water course extending longitudinally of said body, a transverse passageway extending entirely through the body of the drill and intersecting the water course at its lower end, and a tapered straight insert pin positioned within said transverse opening, said insert being formed with passageways communicating with the water course and directing fluid therefrom to the cutting tools, said transverse passageway and insert being tapered to form a tight fit therebetween tending to hold the insert in position.

4. A rotary drill bit for drilling wells comprising a body carrying cutter means at the lower end thereof, a water course extending longitudinally of said body, a transverse passageway extending entirely through the body of the drill and intersecting the water course at its lower end, and a tapered straight insert pin positioned within said transverse opening, said insert being formed with passageways communicating with the water course and directing fluid therefrom to the cutting tools, said insert being of hardened non-abrasive metal.

45 5. A rotary bit for drilling oil wells, which bit comprises a body carrying cutters at the lower end thereof, a water course extending longitudinally within the body of the drill and terminating in a tapered transverse passageway extending entirely through the body of the drill and intersecting the said longitudinally extending water course, and a removable tapered insert positioned within said passageway to fill the same, said insert being formed with an internal 50 passageway, one end of which communicates with the longitudinal passageway of the drill bit body and the other end of which discharges fluid from said longitudinal passageway into the cutting area at a point exterior of said drill bit body.

60 6. A rotary bit for drilling oil wells, which bit comprises a body carrying cutters at the lower end thereof, a water course extending longitudinally within the body of the drill and terminating in a transverse passageway extending entirely through the body of the drill, and a tapered removable insert positioned within said passageway and intersecting said longitudinally extending water course, said insert being formed with an internal passageway, one end of which

communicates with the longitudinal passageway of the drill bit body and the other end of which discharges fluid from said longitudinal passageway into the cutting area at a point exterior of said drill bit body.

7. A rotary bit for drilling oil wells, which bit comprises a body carrying cutters at the lower end thereof, a water course extending longitudinally within the body of the drill and terminating in a transverse passageway extending entirely through the body of the drill, a tapered removable insert positioned within said passageway and intersecting the said longitudinally extending water course, said insert being formed with an internal passageway, one end of which 10 communicates with the longitudinal passageway of the drill bit body and the other end of which discharges fluid from said longitudinal passageway into the cutting area at a point exterior of said drill bit body, said passageway and insert 15 being tapered with relation to each other whereby the insert may be forced tightly into the passageway.

8. A rotary bit for drilling oil wells, which bit comprises a body carrying cutters at the lower end thereof, a water course extending longitudinally within the body of the drill and terminating in a transverse passageway extending entirely through the body of the drill, a tapered removable insert positioned within said passageway and to intersect the said longitudinally extending water course, said insert being formed with an internal passageway, one end of which 25 communicates with the longitudinal passageway of the drill bit body and the other end of which discharges fluid from said longitudinal passageway into the cutting area at a point exterior of said drill bit body, said passageway and insert 30 being tapered with relation to each other whereby the insert may be forced tightly into the passageway, and means at the large end of said tapered insert for holding the insert in its seated position.

9. A rotary drill bit for drilling wells, comprising a body carrying cutter means at the end thereof, a water course extending longitudinally of said body, a transverse passageway intersecting the water course at its lower end and extending entirely through the body of the drill, a tapered water course insert pin positioned 40 within and completely filling said transverse opening, said tapered water course insert pin being formed with passageways communicating with the water course and directing fluid therefrom to the cutting tools.

10. A rotary bit for drilling oil wells which bit comprises a body carrying cutters at the lower end thereof, a water course extending longitudinally within the body of the drill, a tapered transverse passageway extending entirely through the body of the drill and intersecting the longitudinally extending water course at its lower end, a tapered straight insert pin positioned within the transverse passageway, said tapered insert pin being formed with passageways communicating with the water course and directing fluid therefrom to the cutting tools.
